Primary Examiner — Darcey E Gottschalk(74) *Attorney, Agent, or Firm* — Seed Intellectual Property Law Group LLP(57) **CLAIM**

The ornamental design for a lid for jars, as shown and described.

DESCRIPTION

FIG. 1 is a right side, top, front axonometric view of a lid showing our new design;

FIG. 2 is a right side, bottom, rear axonometric view of the lid of FIG. 1 showing our new design;

FIG. 3 is a front elevation view of the lid of FIG. 1;

FIG. 4 is a rear elevation view of the lid of FIG. 1;

FIG. 5 is a right side elevation view of the lid of FIG. 1;

FIG. 6 is a left side elevation view of the lid of FIG. 1;

FIG. 7 is a top plan view of the lid of FIG. 1; and

FIG. 8 is a bottom plan view of the lid of FIG. 1.

FIG. 9 is a right side, top, front axonometric view of a lid showing an alternative embodiment of our new design;

FIG. 10 is a right side, bottom, rear axonometric view of the lid of FIG. 9;

FIG. 11 is a front elevation view of the lid of FIG. 9;

FIG. 12 is a rear elevation view of the lid of FIG. 9;

FIG. 13 is a right side elevation view of the lid of FIG. 9;

FIG. 14 is a left side elevation view of the lid of FIG. 9;

FIG. 15 is a top plan view of the lid of FIG. 9; and,

FIG. 16 is a bottom plan view of the lid of FIG. 9.

In the drawings, the broken lines show portions of a lid for jars that form no part of the claim.

1 Claim, 12 Drawing Sheets(56)
